LATCH

Claude E. Hooper and Ralph L. Chappell,
New York, N. Y.

Application May 16, 1931, Serial No. 537,850

8 Claims. (Cl. 292—255)

This invention relates to door latches and more particularly to foot operated latches or latches operated from a point remote from the door and in which the unlatching of the door is accompanied by an opening of the door and 5 more especially to latches for refrigerator or ice box doors.

Hand operated latches are, as a rule, troublesome and very inefficient especially in refrigerator doors or in doors that must be opened by 10 a person who is carrying objects. In refrigerator doors hand operated latches are especially wasteful, time and energy are expended in placing objects on nearby tables and the tops of refrigerators so that the door may be opened by hand, and the efficiency of the refrigerator is greatly lessened due to the extra time the door is left open while objects to be placed in a refrigerator are retrieved from nearby tables and placed within the refrigerator. In addition to 20 this hand latches are unsightly and offer opportunities for pinching of fingers in the parts of the latch.

The objects of this invention are:

- 25 1. To provide a simple, cheap latch which will in one operation unlatch the door and open the same.
2. To provide such a latch that may be operated by the foot or by other means at a point remote from the door.
- 30 3. To provide such a latch that is easily installed and in no way interferes with the seal of the door or with the insulation of the refrigerator.
4. To provide such a latch that may be easily 35 concealed without interfering with the operation of the door or the refrigerator.
5. To provide such a latch that is simple of construction and manufacture, cheap in cost and entirely practicable.

40 Other objects and advantages of this invention will appear in the following specification. The invention is shown in the drawings in which

45 Figure 1 is a partial elevation of a refrigerator with one modification of the invention installed;

Figure 2 is a sectional view taken on line 2—2 of Figure 1;

50 Figure 3 is a sectional plan view on the line 3—3 of Figure 1;

Figures 4 and 5 are views of the latch in various positions during its operation;

55 Figure 6 is an elevation of a refrigerator partly in section showing a different modification of the invention;

Figure 7 is a view of the catch shown in Figure 6;

Figure 8 is an elevation of the refrigerator with a different modification of the invention installed;

Figure 9 is a sectional view on line 9—9 of Figure 8;

Figure 10 is a sectional plan view on line 10—10 of Figure 8;

Figure 11 is a plan view of the latch bar or bolt of the modification of the invention shown in Figure 8;

Figure 12 is an elevation of the bolt in Figure 11 showing the bolt in closed position;

Figure 13 is a view of the same bolt in the open position;

Figures 14 and 15 are views of a different form of bolt for use in the modification of the invention shown in Figure 8; and

Figure 16 is a view of a catch member adapted for use with the bolt shown in Figures 14 and 15.

In the drawings like characters of reference indicate like parts.

1 is a refrigerator having a door 2 and a door frame or door casing 3.

In the forms of the invention illustrated in Figures 1 to 7 the door 2 has rigidly mounted thereon a bolt 4. This bolt is positioned on the edge of the door and protrudes therefrom as shown. The bolt 4 as shown is round in cross section and a roller may be used on the bolt to reduce friction. The bolt may be of any cross section without departing from the invention.

On the door frame 3 directly opposite bolt 4 is catch member 5. This catch member 5 is a flat piece of metal or other suitable material. Although a flat piece of metal is shown, any other form of catch member can be used if it has the necessary parts as will be described later. The catch member 5 is slideably mounted on the door casing 3 by means of slots 6 and screws 7 extending through these slots and into the door casing 3. Any other means of slideably mounting the catch member may be utilized without departing from the spirit of the invention.

The door casing 3 is cut away as at 10 to form a channel in which the catch member 5 slides and into which the bolt 4 protrudes when the door is closed. This channel is of such depth 50 and so arranged that when the door is closed the bolt 4 protrudes into the channel and the catch member is below the surface of the door casing so that a perfect seal is obtained between the door and the door casing and the latch and 55

bolt are concealed from the inside and the outside of the refrigerator.

The catch member 5 is cut away to form a catch 8 adapted to receive the bolt 4 and a cam surface 9 adapted to cooperate with bolt 4 to open the door. The catch member 5 also has a cam surface 11 adapted to cooperate with the bolt 4 and move the catch member downward as the door is closed.

10 The catch member 5 is so positioned that when it is at its upper sliding position the catch 8 engages bolt 4 to keep the door in a closed position and so that when the catch member 5 is moved downward the cam surface 9 engages the bolt 4 and forces the door outward to open position. When the catch member 5 is at its upper position cam surface 11 is positioned to engage bolt 4 when the door is being closed.

The catch member 5 is operatively connected 20 to a foot pedal 12 which protrudes from the corner of a leg 13 of the refrigerator through a slot 14 in said leg. In Figures 1 and 2 the pedal 12 is connected to the catch member 5 by a metal strip 15 which is a continuation of the catch 25 member 5. In Figures 1 and 2 this metal strip 15 is positioned in the channel 10 which in this form of the invention extends from the catch member 5 to the bottom of the door casing 3. The strip 15 then extends through the wall of 30 the refrigerator at the bottom of the door casing 3 in a slot 16. This slot 16 terminates at its top portion in the seal of the door and at its bottom in the refrigerator. This slot 16 may be in the nature of a stuffing box. In this form of the 35 invention a stop 17 is rigidly fixed to the strip 15. This stop may be of any suitable material such as metal and may have its upper face covered with felt or any sealing material. This stop 17 is so positioned that it contacts with the bottom 40 portion of the box when the catch member 5 is at its upper position.

Directly below the stop 17 is a spring return 45 mechanism. This is shown in the drawings as a coil spring is deposited around the strip 15 but may be any suitable return mechanism. The top of spring 18 bears on stop 17 and the bottom of spring 18 bears on an ear 19 extending inwardly on the leg 13 of the refrigerator. This spring is arranged so that it forces the catch member 5 50 to its upper position.

In the modification shown in Figures 6 and 7 the means connecting the catch member 5 to the pedal 12 comprise a rod 20 of any suitable material. The rod 20 extends through opening 21 in 55 the insulation of the refrigerator down through the bottom of the box. There may be a stuffing box in opening 21. A stiff wire may be used in lieu of a rod. This would require a smaller opening 21 and a felt stopper would suffice for 60 a stuffing box.

In this modification of the invention the bottom portion of catch member 5 is bent up to form an ear 22 having therein a hole 23 adapted to slideably receive the rod 20. At the upper 65 end of rod 20 is a knob 24 or other suitable stopping means to cooperate with the ear 22 to pull catch member 5 to its bottom position when the rod 20 is moved downward. The catch member 5 is mounted in a channel as at 10 similar to the 70 channel shown in Figures 1, 2 and 3 and there is, in addition, in the door casing, a recess 25 into which the ear 22 of catch member 5 protrudes and into which hole 21 opens so that rod 20 protrudes into said recess and through hole 23. A 75 spring return mechanism consisting of a coil

spring 26 is provided. This spring 26 is disposed around the rod 20 and is adapted to urge the catch 5 to its upper position. The upper end of the spring bears on ear 22 and the bottom on the bottom surface of recess 25.

In operation, when the door 2 is in closed position, catch 8 engages bolt 4 as shown in Figure 4 and is held in this position by spring 18 or spring 26, depending upon which modification of the invention is used. A downward force applied to 10 pedal 12 actuates catch member 5 by means of the connecting means 15 or 20. As the catch member 5 moves down catch 8 releases the bolt 4 and cam surface 9 engages bolt 4 forcing the door outward to the open position as shown in 15 dotted lines in Figure 4. The distance the door swings open depends upon the force applied to the pedal 12. When the pedal 12 is released, spring 18 or spring 26 returns the catch member 5 to its upper position. When the door is swung 20 closed bolt 4 engages cam surface 11. This forces catch member 5 down as shown in Figure 5 and the bolt 4 slides over cam surface 11 into catch 8 which is held in engagement with bolt 4 by means of spring 18 or 26 to effectively latch the door. 25 In Figures 1 and 2 the catch member 5 and the connecting means 15 slide as a unit on closing the door when bolt 4 coacts with cam surface 11. In the modification of the invention shown in Figures 6 and 7 the closing of the door and the 30 coaction of bolt 4 and cam surface 11 cause catch member 5 to slide downward. The rod 20 remains practically stationary and the catch member 5 slides along the rod. The sliding action is almost instantaneous and before the rod 20 has time to 35 slide downward the return spring has urged the catch member 5 to its upper position where catch 8 engages bolt 4 to hold the door in the closed position.

The modification of the invention shown in 40 Figures 8 to 16 utilizes a pivoted bolt 104 pivoted at 28 and mounted on the inner side of the door casing 3. Bolt 104 has a roller 36 on the end 34 to cooperate with a catch member. On the inner side of the door 2 is a catch member 105 which 45 has a catch portion 108 and a cam surface 109 both adapted to cooperate with the bolt 104, the catch 108 being adapted to retain the door in a closed position and the cam surface 109 being adapted to force the door outward and to open 50 position when the bolt 104 is pivoted up about the point 28.

In Figures 8 to 13 the bolt 104 is an adaptation of the usual refrigerator hardware. In hand operated latches a somewhat similar bolt 55 is usually mounted on the door of the refrigerator with the catch member 105 mounted on the door casing on the outside of the refrigerator. Figures 11 to 13 show a bolt with a spring return means 29 consisting of a vertical stop 30, a 60 slidably mounted cam surface 31 and a spring 32 tending to force the cam surface 31 toward the stop 30 and to keep the bolt 104 in a horizontal position. Cooperating with the bolt is an ear 33 so arranged that when the bolt 104 is 65 pivoted about the point 28 it contacts with the ear 33 and slides beyond it. The ear 33 then holds the bolt in the upper position as shown in Figure 13. A slight jar will dislodge the bolt 104 from the ear 33 and it will be returned by the 70 spring 32 to the horizontal position. One end of the bolt 104, designated as 34, is adapted to cooperate with catch member 105 and the other end has a slot 35 through which the rod 120 extends. This rod has a knob or stopping means 75

124 thereon so that a downward motion of the rod pivots the bolt 104 about the point 28. This rod 120 is connected to a foot pedal 12 as shown in Figure 8. This rod 120 passes through the 5 wall of the refrigerator in an opening 121.

The rod 120 has a spring return mechanism thereon comprising a spring 118 coiled about the rod as shown in Figures 8 and 9. This spring is so arranged that it contacts with the ear 19 on the inner portion of leg 13 and urges the rod 120 to its upper position.

In operation a downward movement of pedal 12 moves rod 120 down. This moves bolt 104 to the position shown in Figure 13. The end 34 which has been in cooperation with catch 108 to hold the door closed is moved up and unlatches the door. As the upward motion continues the roller 36 on the end 34 contacts with cam surface 109 forcing the door open. The ear 33 then holds the bolt 104 in its up position and the spring return 118 forces the rod 120 to its up position as soon as the pedal 12 is released. On closing the door the cam surface 109 strikes the bolt 104 and releases it from ear 33. The 20 bolt then returns to the vertical position and cooperates with catch 108 to close the door and the latch is set for operation.

Figures 14, 15 and 16 show another type of pivoted bolt. The bolt has slot 35 at one end cooperating with rod 120 and knob 124 as above explained. The springs 37 and 38 are arranged to keep the bolt 104 in its down position as shown in Figure 15. A downward movement of rod 120 caused by pressure on pedal 12 moves the bolt 35 104 to the position shown in Figure 14 which causes the opening of the door through the cooperation of the roller 36 and cam surface 109. As soon as the pedal 12 is released the springs 37 and 38 force the bolt to the position shown in Figure 15 where the stop 39 holds the bolt against further downward movement. The 40 catch member 105 in this modification is provided with a cam return surface 111. When the door is closed the cam surface 111 cooperates with the roller 36 to force the bolt 104 up and into catch 108.

In operation a downward force applied to pedal 12 rotates the bolt 104 about the point 28 by means of the coacting means 120. The bolt 104 as it is raised releases the latch by removing the bolt from the catch 108 and on upward movement the bolt 104 cooperates with the cam surface 109 to force the door out and open. In the modification shown in Figures 8 to 13 the bolt 4 remains in the up position contacting with ear 33. When the door is closed cam 109 strikes the bolt and a latching is effected through cooperation between bolt 104 and catch 108. In the modification of the invention shown in Figures 14 to 16 when the foot pedal is released the springs 37 and 38 force the bolt to the position shown in Figure 15. As the door is closed cam surface 111 engages bolt 4 and raises the bolt. As the door is closed bolt 104 passes over this cam surface and engages catch 108 to hold the door in closed position.

While several forms of the device have been illustrated, it is obvious to those skilled in the art that there are many other modifications that 70 might be made without departing from the spirit of the invention.

What we claim is:

1. A door latch comprising a bolt rigidly fixed in the edge of a door, a catch member slidably mounted for vertical movement in a channel in

the door casing and opposite said bolt, said catch member having a cut away portion forming a catch adapted to cooperate with said bolt to hold the door in a closed position when the catch member is urged to its upper position and a 5 cam surface adapted to cooperate with said bolt to open said door when said catch member is moved to its bottom position and a cam surface adapted to cooperate with said bolt to move said catch member to its lower position when the door is being closed, an ear on said catch member extending into a recess at the lower portion of the channel in the door casing, said ear having an aperture adapted to slidably receive a rod, a vertical rod projecting through said aperture 15 and having a head adapted to cooperate with said ear to move said catch member downward, a coil spring disposed around said rod and adapted to cooperate with said ear to force said catch member to its upper position and a foot pedal 20 adapted to impart to said rod a vertical movement.

2. A door latch comprising a bolt rigidly fixed in the edge of a door, a catch member slidably mounted for vertical movement on the door casing and opposite said bolt, said catch member having a cut away portion forming a catch adapted to cooperate with said bolt to hold the door in a closed position when the catch member is urged to its upper position and a cam surface 30 adapted to cooperate with said bolt to open said door when said catch member is moved to its bottom position, an ear on said catch member having an aperture adapted to slidably receive a rod, a vertical rod projecting through said aperture 35 and having a head adapted to cooperate with said ear to move said catch member downward, a coil spring disposed around said rod and adapted to cooperate with said ear to force said catch member to its upper position and a foot pedal 40 adapted to impart to said rod a vertical movement.

3. A door latch comprising a bolt rigidly fixed in the edge of a door, a catch member slidably mounted for vertical movement on the door casing and opposite said bolt, said catch member having a cut away portion forming a catch adapted to cooperate with said bolt to hold the door in a closed position when the catch member is urged to its upper position and a cam surface 50 adapted to cooperate with said bolt to open said door when said catch member is moved to its bottom position, an ear on said catch member having an aperture adapted to slidably receive a rod, a vertical rod projecting through said aperture 55 and having a head adapted to cooperate with said ear to move said catch member downward, a spring adapted to force said catch member to its upper position and a foot pedal adapted to impart to said rod a vertical movement. 60

4. A door latch comprising a bolt, a catch member having a catch and a cam surface adapted to cooperate with said bolt to open said door, means for causing relative movement between said bolt and said catch member to unlatch the bolt and open the door, a spring adapted to hold said catch in cooperation with said bolt, a second cam surface on said catch member adapted to cooperate with said bolt to cause relative movement between said bolt and said catch member on closing the door and a foot pedal adapted to actuate said means and directly connected to said first mentioned means for causing relative movement between said bolt and said catch member for unlatching the latch and opening 70 75

the door, whereby movement of said pedal causes a corresponding movement of said catch member.

5. In an ice box lock and door opener, the combination of a bolt on the edge of the door, a keeper comprising an angle member having a cut-away portion to engage the bolt to hold the door closed, and a cam portion adapted on movement of said keeper to engage said bolt after it is disengaged from said cut-away portion to urge 10 the door outwardly, and a foot pedal adapted to cause movement of said keeper.

6. A door latch comprising a bolt in the edge of a door, a member slidably mounted for vertical movement in a channel in the door casing 15 and opposite said bolt, said member having a cut away portion forming a keeper adapted to cooperate with said bolt to hold the door in a closed position when said member is urged to its upper position, and a cam surface adapted to cooperate 20 with said bolt to open said door on movement of said member to its bottom position, and a foot pedal connected to said member to impart a movement thereto corresponding to the movement of said foot pedal whereby the force applied 25 by said cam surface varies according to the force applied to said foot pedal.

7. A door latch comprising a bolt, a member having a keeper and a cam surface adapted to cooperate with said bolt on a single movement which releases said keeper and then causes said cam to engage said bolt to open said door, and a foot pedal connected to said member to impart a movement thereto corresponding to the movement of said foot pedal whereby the force applied by said cam surface varies according to the force applied to said foot pedal. 5

8. A door latch and opening mechanism comprising a bolt rigidly mounted in the edge of a door, a catch member having a portion to engage the bolt to hold the door in closed position, and a cam surface adapted after the bolt is released 15 from said bolt engaging portion of the catch to cooperate with said bolt to open the door, and a foot pedal, means connecting said foot pedal directly to said catch, whereby the operation of said catch and the coaction of said cam surface with 20 said bolt is controlled by said foot pedal so that force applied to the foot pedal is directly proportional to force applied by said cam surface to said bolt.

CLAUDE E. HOOPER. 25
